METHOD OF COAT CONSTRUCTION

Frank J. Di Biase, Brooklyn, N. Y.

Application August 15, 1935, Serial No. 36,423

3 Claims. (Cl. 2—98)

This invention relates to coat constructions and more particularly to an improved method of coat constructions.

An object of this invention is to provide an improved method for assembling the body of the coat and the collar so as to eliminate any bulge or enlargement at the ends of the collar.

Another object of this invention is to provide an improved method of securing a collar to a garment having a lapel irrespective of the configurations of the collar and the lapel so as to provide a neat joint or connection at the ends of the collar.

A further object of this invention is to provide an improved method of securing a collar to a garment having a lapel, where the collar is initially sewed together and formed and then attached to the garment, the garment preferably being one constructed of relatively cheap material but presenting a finish similar to a garment constructed of higher grade material.

Still another object of this invention is to provide an improved method of attaching a collar to a garment which is such as to reduce the cost of assembling the garment and which is also such as to permit the assembling operation to be made by unskilled workers, while at the same time retaining the appearance of a garment of the better grade.

The above and various other objects and advantages of this invention will in part be described in, and in part be understood from the following detail description of the present preferred embodiment, the same being illustrated in the accompanying drawings wherein:—

Figure 1 is a fragmentary rear elevation of the first step in the method of assembling the collar and the body of a garment in accordance with the hereinafter described method.

Figure 2 shows an inside view of the collar with the body of the garment open and shows the second step in the assembling operation.

Figure 3 is a fragmentary side elevation of the garment showing another step in the assembling operation.

Figure 4 is a fragmentary side elevation of the garment showing an additional step in the assembling process.

Figure 5 is an enlarged sectional view taken on the line 5—5 of Figure 1, showing the collar initially tacked at an end to the body of the garment.

Figure 6 is a similar view but showing the material at the point of tacking cut away.

Figure 7 is an enlarged sectional view taken on the line 7—7 of Figure 9.

Figure 8 is a fragmentary plan view of the collar.

Figure 9 is a fragmentary front elevation of the garment in completed form.

Figure 10 is a fragmentary front elevation of a modified form of this invention.

Referring to the drawings wherein like numerals of reference designate corresponding parts throughout the several views, and first to Figure 1, the numeral 10 designates generally a facing and the numeral 11 designates a front which is cut in accordance with a selected pattern. The two fabrics 10 and 11 may be stitched together by means of stitching 13 and a lapel 12 is formed in the usual manner at the ends of the neck portion 14 of the two pieces of material 10 and 11.

In Figure 8, there is disclosed a collar construction which is adapted to be combined with the body of the garment formed by the fabrics 10 and 11 and this collar comprises an outer fabric 15 and a facing or under collar portion 16. At a point closely adjacent each end of the collar, which is generally designated as 17, there are provided notches 18 and 19 in the two fabrics 15 and 16.

The first step in the assembling operation of the body of the garment with the collar is the initial tacking or securing as by stitching of the collar 17 to the body of the garment. This is effected while the front 11 and the facing 10 are in reversed position and then the four pieces of material, that is, the pieces designated 10, 11, 15, and 16, are stitched together with a collar 17 being disposed at its ends between the front 11 and the facing 10. This stitching which is designated 20 extends from the notch 21 at the inner end of the lapel 12 to the notches 18—19 in the collar, the body of the garment being also notched at a point a short distance away from the notch 21, as 22.

When the ends of the collar 17 are tacked onto the body of the garment by the tacking 20 which engages through the four pieces of material for a relatively short distance along the length of the collar, the front 11 is stitched to the outer collar piece 15, as by stitching 23, which extends from one point of tacking to the other or entirely across the neck portion of the garment. The facing 10 is then stitched as by stitching 24 to the under collar member 16 in the same manner as the outer collar member 15, namely from one point of tacking to the other so that the collar 17 is sewed to the body of the garment with the two collar portions sewed separately to the two body

portions with the exception of the ends of the collar which are tacked as by the stitching 20 to both sections of the body.

After the collar has been firmly secured to the body of the garment, a line of stitching 25 is placed along the lapel 12 and extends parallel with the tacking 20 to substantially the stitching 23 and 24, as shown in Figure 3, this line of stitching being used for the purpose of straightening the upper edge of the lapel 12. After the garment has been sewed by the stitching 25, that portion of the body of the garment end of the collar between the ends of the collar and the notches 18-19 and the notch 22 is removed, as shown in Figure 4, the material being cut relatively close to the tacking 20 and to the parallel stitching 25 at this point.

The garment with the collar attached thereto may then be turned right side out and the seams connecting the collar with the body on both the front portions and the facings may then be pressed down or felled and the front member 11 and the facing or inner member 10 then connected together by stitching passing through the felled portion 26 of the front 11, as shown in Figure 7. In this manner, the front and facing portions of the garment are sewed together with the front portions of each part thereof and the facing portions of each part thereof separately connected together. After the garment has been turned right side out, the lapel may be basted or stitched along the marginal portions thereof inwardly of the stitching 13 so that the entire garment will present a neat appearance and so that the seams will not separate under varying strains to which they may be subjected.

The method hereinbefore described by which the collar is attached to the body of the garment has been in use for a period of time and in addition to providing a neat appearing garment of the cheaper grade, the method also has the effect of reducing the manufacturing cost for each garment while at the same time permitting the use of inexperienced workers in the manufacture of the garment.

I do not wish to be limited to the particular configuration of the garment herein disclosed as it is obvious that the garment may be of any desired style having a lapel thereon and that this garment may be of a type used for children or adults of either sex.

This method of manufacturing the garment eliminates the necessity for basting the collar onto the body of the garment in addition to eliminating any bulge or puckering between the

collar and the body of the garment, the bulge being usually at the ends of the collar in garments of the cheaper grade.

In Figure 10 there is shown another method of securing the collar to the coat body wherein the top collar 15' is tacked, as by tacking 20', between the front 11' and the facing 10'. This form of construction is for the better types of garments and in this construction the under collar 17' has the raw lower edge thereof felled, as by stitching 27, to the facing 10'. In other words, the top collar 15' is the only piece of material which is tacked between the front 11' and the facing 10' and the top collar 15' is stitched as by stitching 23' after the manner of the stitching 23. This felling 27 may be done either by hand or by a suitable machine employing the fell stitch.

I claim:—

1. The method of coat construction which comprises initially forming a collar of at least two pieces of material and stitching three sides of the material together, initially stitching the front and facing of the coat body together with the neck portions of the front and facing free, 25 tacking the ends of the collar through the front and facing of the coat body with a single line of stitching, stitching the balance of one portion of the collar to the facing and stitching the balance of the other portion of the collar to the 30 front of the coat.

2. The method of coat construction which comprises tacking a portion of each end of the collar to the body of the coat between the reversed front and reversed facing of the coat body, stitching the remaining portion of the collar to the body and cutting off that portion of the collar outwardly of the tacking for substantially the full length of the tacking.

3. The method of coat construction which comprises initially forming the collar and coat body of at least two plies of material, notching the collar adjacent each end at a point inwardly of the ends, tacking that portion of both plies of the collar between the two plies of the coat body for 45 the length of the collar from the end to the notch, stitching the remaining portion of the collar to the coat body, stitching the coat body along the lapel thereof and into the body parallel with the tacking for substantially the length of the tacking and then cutting off that portion of the body and the collar outwardly of the tacking between the notch and the adjacent end of the collar.
